Des. 242,359
Patented Nov. 16, 1976

242,359

FACSIMILE TRANSCEIVER

John W. Bruce, Wilton, Conn., assignor to Graphic Sciences, Inc., Danbury, Conn.

Filed May 5, 1975, Ser. No. 574,207

Term of patent 14 years

Int. Cl. D16—03

U.S. Cl. D26—14 R

Fig. 1.

Fig. 2.

Fig. 3.

Fig. 5.

Fig. 4.

Fig. 6

Fig. 7

FIG. 1 is a front perspective view of a facsimile transceiver showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right end elevational view thereof; and

FIG. 7 is a left end elevational view thereof.

I claim:

The ornamental design for a facsimile transceiver, substantially as shown and described.
